UNITED STATES PATENT OFFICE

133,009

DESIGN FOR A FOUNTAIN COMB

Norman R. Metzler, York, Pa.

Application April 1, 1942, Serial No. 106,418

Term of patent 7 years

To all whom it may concern:

Be it known that I, Norman R. Metzler, a citizen of the United States, residing at York, in the county of York and State of Pennsylvania, have invented a new, original, and ornamental Design for a Fountain Comb, of which the following is a specification, reference being had to the accompanying drawing, forming part thereof.

I claim:

The ornamental design for a fountain comb, as shown.

NORMAN R. METZLER.
